A. O. JONES

WARM AIR REGISTER DAMPER OPERATOR

Filed Jan. 26, 1922

Inventor

Almon O. Jones,

By Edwin Guthrie,

Attorney

UNITED STATES PATENT OFFICE.

ALMON OAK JONES, OF BATTLE CREEK, MICHIGAN, ASSIGNOR TO UNITED STATES REGISTER COMPANY, OF BATTLE CREEK, MICHIGAN, A CORPORATION OF MICHIGAN.

WARM-AIR-REGISTER DAMPER OPERATOR.

Application filed January 26, 1922. Serial No. 531,984.

This invention relates to warm air register damper operators, by which is meant the device intended to be directly actuated by the hand of the person desiring to control the flow of warm air through the register and into the room in the wall of which the register is situated. It is the purpose and function of such devices to enable the person seeking to move the damper to arrange the same in any chosen position between full open position and its closed position, and to sufficiently hold the damper in its adjusted position by frictional contacts set up between parts of the device itself. To this description of devices the present invention belongs, and it comprises a register damper operator fashioned from a single piece of bendable and elastic sheet metal bent upon itself to form certain defined members or elements having special construction and operation whereby it is believed material economy in manufacturing is attained, and that the device may be very quickly placed in position and as readily removed for repairs or replacement, and that it is especially effective and reliable in its action and service.

The construction and arrangement of the parts of this invention are shown in the accompanying drawings of which Fig. 1 represents a vertical section of a warm air register box having this invention applied thereto and illustrating the position in which the device is located upon the register. Fig. 2 is a vertical section, approximately full size, showing a portion of the open-work lattice or front of the register with the damper pivoted thereon and this invention supported thereby. Fig. 3 is a front view of this invention by itself. Fig. 4 is a back view. Fig. 5 is a vertical section on the broken line 5-5 of Fig. 4. In all the figures after Fig. 1 the scale of drawing is about full size.

Throughout the description and drawings the same letter is employed to refer to the same part.

Considering the drawings, the register box of any chosen shape has the customary open work face plate or front B, which may be of any selected pattern, and may be removable or in one piece with the box. The usual opening in the front of the box through

which the warm air passes outwardly is bounded by the inwardly turned flanges *a* 55 as illustrated in Fig. 1. These flanges are particularly useful in warm air registers as they act to direct the flow of air entirely through the opening in the front of the register box, and do not allow small streams of air to escape laterally which as a general thing results in dust streaks upon the adjoining wall or wall paper. By the use of the flanges as shown that objection does not occur. 60 65

As will be noted in Figs. 1 and 2, the pivotal connection *b* couples the damper C and the register front B, and the damper has the slot *c* near the top.

The front B of the register is provided 70 with a pair of spaced ears near the top, one of which designated by the letter D is shown in Figs. 1 and 2. Those ears D support a pivot pin or bolt *d*, which in turn pivotally upholds the device constituting the main subject-matter of this invention. This device comprises a single piece of bendable and elastic sheet metal bent upon itself to form a head E, which is the finger piece grasped by the fingers to actuate the damper. From the head there extends the curved and grooved body *e*, as best illustrated in Figs. 3, 4, and 5, and the body has a pair of spaced ears *F* and *f*, that are provided with corresponding openings for the passage of 80 85 the pivot pin *d*.

As will be observed in Figs. 2 and 5, the end of the body *e* is provided with the inwardly extending lugs *G* and *g*, one on either side of the end of the body. 90

The single piece of metal of which this invention is made is also formed into the back piece H, and the back piece passes in a curving direction between the ears of the body curving towards the body and then curving outwardly and downwardly and terminating near the end of the body *e* where it is provided with a pair of lugs *h* and *h'* as shown in Figs. 2 and 5. These lugs project towards the lugs *G* and *g* of the body *e* as illustrated. It will be noted in Figs. 1 and 2 that the back piece H passes through the slot *c* in the damper, and that the ends and lugs of the body and back piece are arranged upon opposite sides of 100 105 the damper.

In Fig. 4 is shown the expanding spring J having its end coils placed against the inside surfaces of the ears F and f of the body, and in the operation of this invention the tendency of the spring J is to spread the ears F and f apart, and when this invention is in service position between the ears D of the register front, the ears F and f are spread into frictional contact with the ears 10 D and the damper may be held in any desired position into which it may be adjusted, between its full open position, or partly open as it appears in Fig. 1, or closed as it appears in Fig. 2. As stated, this invention 15 is made of metal more or less elastic, and, considering Figs. 1 and 2, it will be understood that the ends of the parts referred to by the letters G and h are elastically separable to a certain extent. The 20 reason for this is that many persons in opening and closing a register damper or plate such as the damper C, do so very roughly, often with the foot, and the elastic capacity of this invention in a measure cushions the 25 blows and prevents the bending of connected sheet metal parts.

Having now described the special construction and arrangement of the parts of

this invention, and explained the mode of its operation, what I claim is:—

A warm air register damper operator, comprising a single piece of bendable and elastic metal bent upon itself to form a head, a curved and grooved body extending from the said head and provided with spaced ears located intermediately with respect to the said head and the end of the body, said ears having openings for the passage of a pivot pin, a curved and grooved back piece extending from the said head and passing between the said ears of the body and terminating near the end of the said body, a spring arranged across the said back piece and bearing upon the said ears to spread the ears apart, a register front, a damper pivoted to the register front and passing between the said body and back piece of the said damper operator, and the said register front having ears arranged against the said ears of the damper operator whereby the said spring holds the said ears in frictional contact.

In testimony whereof I affix my signature.

ALMON OAK JONES.
